UNITED STATES PATENT OFFICE.

GEORGE PLANTA BARNES, OF BROMLEY, ENGLAND.

APPARATUS FOR SPRAYING LIQUIDS.

No. 800,259.

Specification of Letters Patent.

Patented Sept. 26, 1905.

Application filed November 29, 1904. Serial No. 284,707.

To all whom it may concern:

Be it known that I, GEORGE PLANTA BARNES, engineer, a subject of the King of Great Britain and Ireland, residing in Bromley, county of Kent, England, have invented certain new and useful Improvements in and Relating to Apparatus for Spraying Liquids, of which the following is a specification.

This invention relates to apparatus for spraying liquids, and has for its object to provide a simple and efficient means for spraying liquids and one which can be readily adjusted, will be reliable in use, and may be used in almost any liquid without the orifices becoming clogged.

Apparatus for spraying liquids made in accordance with my invention comprises a trough or receptacle in which the liquid is disposed, a nozzle having two or more ducts with apertures of the same or of different sizes disposed at or near the surface of the liquid, the said ducts or apertures being at an angle to each other and one or both at an angle to the liquid to be sprayed and through which ducts or apertures a blast of steam, air, or other vapor acts upon the liquid outside to spray or spread the same.

Referring now to the drawings, Figure 1 is a front elevation, partly in section. Fig. 2 is a plan of same. Fig. 3 is a sectional side elevation, and Fig. 4 a section of a modified form of apparatus made in accordance with my invention. Figs. 5 and 6 are sectional views of two forms of nozzle made in accordance with my invention and their position in relation to the liquid.

In the form of apparatus shown in Figs. 1, 2, and 3 and adapted for use in damping or spraying webs of paper or other materials in the manufacture or in the subsequent use thereof I employ a trough *a*, disposed in a suitable position relative to the web to be damped or sprayed. The trough *a* is adapted to be kept nearly full with liquid, a running-tap *b* and a regulating overflow-pipe *c* in the trough *a* maintaining it at the required constant level. Above the trough *a* and transversely to the web is disposed a sliding frame or bar *d*, upon which are mounted brackets or guides *e*, having adjustable carriers *f* thereon. At the back of the trough and parallel with the frame *a* is a compressed-air-supply pipe *g*, having several branches *h*, which terminate in nozzles *j*. The nozzles are adapted to rest in and be supported by the carriers *f*, each nozzle or pair of or section of nozzles being capable of being regulated as toward the liquid independently of the others by screwed handles *k*, working between the carrier *f* and the bracket *e*. The frame or bar *d* is adapted to be raised by cams *m* for the purpose of raising or adjusting the level of all the nozzles simultaneously. The nozzles *j* are preferably provided with two holes *n* *o*, inclined to one another, and I find that an ordinary gas-burner having two orifices inclined to one another, as shown in Fig. 5, well suited for some purposes, while for other purposes best results are obtained by having the upper hole parallel, or nearly so, with the liquid in the trough, the lower hole being at an angle thereto, as shown in Fig. 6.

In use for damping webs of paper or other materials the trough *a* is first filled from the running-tap *b* with water or other liquid to be sprayed until it overflows at *c*. The nozzles *j* are then separately adjusted, preferably so that the lower hole *o* is slightly below or on a level with or sufficiently near the surface of the liquid, the other hole *n* being close to and directly above it, that when the blast is applied the liquid outside the hole *o* of each nozzle is by the combined influences of suction and capillary attraction lifted and partly broken up, to be still further broken up by the blast coming through the hole or holes above, and the fine spray is blown out over the edge of the trough onto the web.

In some cases the holes *n* and *o* may be duplicated. The frame or bar *d*, carrying the nozzles *j*, can then be raised or lowered, according as it is desired to adjust the volume of the liquid in the spray, or this result may be obtained by raising or lowering the overflow-pipe *c*, thus dispensing with the sliding bar *d* and the cams *m*, the nozzles in this case being fixed at an exact level as to the liquid.

The branch pipes *h* may be partly made of rubber or other flexible hose to permit of each nozzle being raised or lowered, or in some cases the supply-pipe *g* may be pivoted or the branch pipes *h* provided with flexible joints for the same purpose.

In the modified form shown in Fig. 4 the liquid is brought to the nozzle *j* by means of a pipe *p* instead of a trough, and the nozzle *j* is so adjusted in relation to the pipe *p* that the blast coming from the air-pipe *h* through the said nozzle will spray the liquid from and over the edge of the pipe *p*.

When used for the purpose of spraying liquid fuel, the same form of nozzles and orifices are used, the supply of liquid to each nozzle or pair or sections of nozzles being through an independent pipe, such as *p*, all connected, however, outside the furnace to a general supply of liquid kept at a desired level. In the case of furnaces liable to movement, such as in ships or trains, the pipes and nozzles, together with the general supply of liquid for the nozzles, are governed automatically so as to spray the liquid from each nozzle without variation in quantity.

What I claim, and desire to secure by Letters Patent, is—

1. In apparatus for spraying liquids, the combination of a plurality of ducts adapted for connection to a fluid-compressor, a plurality of said ducts being inclined toward a common point, a chamber adapted to contain the liquid to be sprayed, the ducts being disposed in such a position with relation to the surface of the liquid in the chamber that the liquid is raised from said chamber and sprayed without passing through any ducts, substantially as described.

2. In apparatus for spraying liquids, the combination of a pressure-fluid-supply pipe, a nozzle at the end of said supply-pipe, a plurality of orifices in said nozzle and inclined to one another, a chamber adapted to contain the liquid to be sprayed, the nozzle being disposed in such a position that the liquid is sprayed without passing through the nozzle, substantially as described.

3. In apparatus for spraying liquids, the combination of a pressure-fluid-supply pipe adapted for connection to a fluid-compressor, a nozzle at the end of said supply-pipe, a plurality of orifices in said nozzle and inclined to one another, a chamber adapted to contain the liquid to be sprayed, and means for adjusting the relative positions of the nozzle and the liquid so that the liquid is sprayed without passing through the nozzle, substantially as described.

4. In apparatus for spraying liquids, the combination of a fluid-supply pipe adapted for connection to a fluid-compressor, a nozzle at the end of said fluid-supply pipe, a plurality of orifices in said nozzle and inclined to one another, a chamber adapted to contain liquid, and means for adjusting the relative positions of the nozzle and the liquid, substantially as described.

5. In apparatus for spraying liquids, the combination of a fluid-supply pipe adapted for connection to a fluid-compressor, a nozzle at the end of said fluid-supply pipe, a plurality of orifices in said nozzle and inclined to one another, a chamber adapted to contain liquid, means for raising and lowering the nozzle in relation to the liquid, and means for altering the relative positions of all the nozzles col-

lectively to the liquid, substantially as described.

6. In apparatus for spraying liquids, the combination of a fluid-supply pipe adapted for connection to a fluid-compressor, a nozzle at the end of said fluid-supply pipe, a plurality of orifices in said nozzle and inclined to one another, a liquid-supply pipe adapted to convey liquid to the orifices of the nozzle, and means for raising and lowering the nozzle in relation to the liquid, substantially as described.

7. In apparatus for spraying liquids, the combination of a fluid-supply pipe adapted for connection to a fluid-compressor, a plurality of nozzles connected to said fluid-supply pipe, a plurality of orifices in each nozzle and inclined to one another, a liquid-supply pipe adapted to convey liquid to the orifices of the nozzles, means for raising and lowering each nozzle separately in relation to the liquid, and means for raising and lowering all the nozzles collectively in relation to the liquid, substantially as described.

8. In apparatus for spraying liquids, the combination of a fluid-supply pipe, a nozzle at the end of said fluid-supply pipe, a plurality of orifices in said nozzle and inclined to one another, means for connecting the fluid-supply pipe to a fluid-compressor, a chamber adapted to contain liquid, and means for conveying liquid to the chamber, substantially as described.

9. In apparatus for spraying liquids, the combination of a fluid-supply pipe adapted for connection to a fluid-compressor, a nozzle at the end of said fluid-supply pipe, a plurality of orifices in said nozzle and inclined to one another, a chamber adapted to contain liquid, means for conveying liquid to the chamber, and means for altering the relative positions of the liquid and nozzle, substantially as described.

10. In apparatus for spraying liquids, the combination of a fluid-supply pipe adapted for connection to a fluid-compressor, a plurality of nozzles connected to said fluid-supply pipe, a plurality of orifices in each nozzle and inclined to one another, a chamber adapted to contain liquid, means for raising and lowering each nozzle separately in relation to the liquid, a bar to which all the nozzles are attached, and a cam for raising and lowering said bar so as to raise or lower said nozzles collectively in relation to the liquid, substantially as described.

11. In apparatus for spraying liquids, the combination of a fluid-supply pipe adapted for connection to a fluid-compressor, a plurality of nozzles connected to said fluid-supply pipe, a plurality of orifices in each nozzle and inclined to one another, a chamber adapted to contain liquid, a liquid-supply pipe adapted to convey liquid to the orifices of the nozzles,

means for raising and lowering each nozzle separately in relation to the liquid, means for raising and lowering all the nozzles collectively in relation to the liquid, and an overflow-pipe 5 disposed in the chamber, substantially as described.

In witness whereof I have hereunto signed

my name in the presence of two subscribing witnesses.

GEORGE PLANTA BARNES.
